United States Patent

Des. 240,429
Patented July 6, 1976

240,429

SHOWER HEAD

Clifford E. Grube, Niles, Ill., assignor to
Associated Mills, Incorporated

Filed Aug. 18, 1975, Ser. No. 605,262

Term of patent 14 years

Int. Cl. D23—01

U.S. Cl. D23—35

FIG.1

FIG.2

FIG.3

FIG.4

FIG.5

FIG.6

FIG. 1 is a side elevational view of a shower head showing my new design;

FIG. 2 is an elevational view taken from the side opposite that shown in FIG. 1;

FIG. 3 is a top plan view thereof;

FIG. 4 is a bottom plan view thereof;

FIG. 5 is a front elevational view thereof; and

FIG. 6 is a rear elevational view thereof.

I claim:

The ornamental design for a shower head, as shown.
